ALFRED SCHWARZ, OF MONTCLAIR, NEW JERSEY

APPARATUS FOR GASIFYING OIL

Application filed March 29, 1927. Serial No. 179,287.

My invention relates to apparatus for gasifying oil and more particularly has reference to such apparatus wherein carbon deposition is obviated or reduced to a minimum.

In my companion application No. 159,093, filed January 5, 1927, I have disclosed a process and apparatus for effecting the distillation of oil and for converting into gas the residue resulting therefrom. The present invention is directed to a specific form of apparatus employed in such process to obtain as near as possible, perfect gasification of the residual oil.

In the gasification of oil, particularly in the case of heavy oil, steam temperatures as high as 1400° F. are employed and as a result excessive amounts of carbon are usually formed which soon coat the heating apparatus, making further operation impossible, unless this excessive carbon is in some way taken care of. It is common practice to atomize oil by means of steam, the resultant carbon, when the proper temperatures are reached, combining with the oxygen which results from the decomposition of the steam thereby forming carbon monoxide, carbon dioxide, and many other gases, particularly those of the fatty acid series.

Irrespective of the nature or composition of the ultimate gas, it is necessary to make available at the moment of decomposition of the oil, oxygen in a nascent state for immediate combination with the carbon. If no oxygen is present in a nascent condition, excess carbon is deposited on the walls of the heating receptacle and the heat conductivity thereof is greatly impaired. Such carbon is usually deposited in more or less homogeneous form and I have found that higher temperatures are required to convert this carbon into gases. Presumably steam does not penetrate the carbon in homogeneous form until it is sufficiently heated to become loose in structure. It is therefore of utmost importance that the oil be very finely atomized and that the steam employed for atomization be hot enough to react therewith.

It is therefore an object of this invention to provide a device for the gasification of oil wherein oil is finely atomized by means of

steam at a decomposing temperature wherein deposition of carbon on the walls of the apparatus is obviated.

According to my invention the oil is atomized and gasified by direct contact with superheated steam, the atomizing device being of such construction that carbon is not given an opportunity to deposit upon heated walls.

In the accompanying drawings forming a part of this application, the single view represents a vertical section through my improved atomizer or gasifying device.

In the drawing, A indicates generally an outer casing having oil inlet 1 leading to oil chamber 1^a. A duct 2 controlled by a needle valve 3 conducts oil from chamber 1^a to the point of atomization. The needle valve 3 is adjusted for proper oil flow by means of handle 3^a. In the casing is formed superheated steam inlet 4 leading to steam chamber 5 formed between the nozzle 6 and the inner wall 6^a. The nozzle 6 is vertically adjustable by reason of its threaded engagement with the interior portions of the casing as shown. Leading from the steam chamber 5 and nozzle 6 is a Venturi tube 7 for flow of the atomized oil and steam. Within the casing and surrounding the atomizer and the Venturi tube 7 is a compartment or jacket 8 having an inlet 9 for the introduction of any suitable cooling fluid such as saturated steam or even water. The term cooling is merely a relative one as compared to the high temperatures of the steam introduced at inlet 4 for atomization of the oil. The cooling fluid is discharged from the casing through outlet 10. Formed within the nozzle and surrounding the oil duct 2 is an annular chamber 11 communicating with the jacket 8 through the ports 12.

In operation the nozzle 6 is first adjusted so as to pass into the throat of the Venturi tube 7 a given amount of steam per unit of time, say for example, 150 pounds per hour. Oil heated to a temperature of about 700° F. is introduced through inlet 1, preferably under pressure, to oil chamber 1^a, the flow of oil from chamber 1^a through duct 2 being regulated by the needle valve 3. Steam superheated to a temperature of 1400° F. or higher

and under considerable pressure, for example 100 pounds per square inch, is introduced through inlet 4 to the steam chamber 5, filling said chamber at the pressure stated. It is 5 essential that the steam enter chamber 5 under full pressure and should not be throttled prior to its introduction thereinto in order to obtain maximum velocity when the oil and steam are mixed in the throat of Venturi tube 7, thus insuring maximum mechanical force 10 for the atomization of the oil. The oil should not be excessively heated prior to its atomization for otherwise carbon deposition will occur. From the drawing it will be seen that 15 the nozzle 6 serves as a control valve for the steam chamber 5 whereby the flow of steam into the Venturi tube may be regulated. Superheated steam issuing from chamber 5 effects a very fine atomization of the oil passing 20 through duct 2, the oil being substantially gasified by reason of the high temperature steam. The gaseous mixture is projected through Venturi tube 7 for further treatment, such as scrubbing, purification, etc., and collection. 25

Under ordinary conditions, the heated mixture, by contact with the walls of the atomizer would necessarily heat such walls to a 30 temperature in the neighborhood of the superheated steam temperature, for example to about at least 1000° F. At such temperatures the oil would carbonize, producing heavy deposits of carbon which would soon clog up the apparatus. In the present device, however, a cooling medium such as saturated steam, hot water, etc., is circulated through 35 the jacket 8 surrounding the atomizer and Venturi tube thus maintaining the heated walls at a temperature below that at which carbonization thereon would occur. As pointed out above, the cooling is only relative and need not be very great, it being only essential to cool to below a carbonizing temperature. The cooling medium also circulates 40 from jacket 8 into and through the annular chamber 11 by way of ports 12 thereby preventing the heated oil from carbonizing within and clogging up the duct 2.

From the foregoing it will be seen that I 50 have devised a rather simple apparatus for gasifying oil wherein the oil is finely atomized and gasified by direct contact with superheated steam without supplying heat to the oil through metallic walls which are readily 55 susceptible to carbon accumulation. Furthermore, in my device, such parts as would ordinarily become highly heated by contact with hot oil and superheated steam are constantly 60 maintained at a temperature below that at which carbonization would occur.

The invention is by no means limited to the particular construction shown and described 65 but is capable of various changes and modifications without departing from the spirit

and scope of the invention as defined in the appended claims.

Having described my invention, what I claim as new and desire to secure by Letters Patent of the United States is:

1. An apparatus for gasifying oil comprising a casing, an atomizer within said casing, means for supplying oil and steam to said atomizer, a tube formed by said casing and communicating with said atomizer for discharging atomized oil and steam, a jacket in said casing surrounding said atomizer and tube, and in heat-exchanging relationship therewith, and means for introducing a cooling medium to said jacket. 70

2. An apparatus for gasifying oil, comprising a casing, an oil chamber within said casing, a nozzle in said casing having an oil duct in communication with said chamber, a steam chamber in said casing surrounding a portion of said nozzle, a Venturi tube within said casing leading from said steam chamber and duct for discharging atomized oil and steam, a jacket in said casing surrounding said Venturi tube, and in heat-exchanging relationship therewith, and means for introducing a cooling medium to said jacket. 75

3. An apparatus for gasifying oil, comprising, a casing, an adjustable nozzle in said casing, a duct in said nozzle, means for feeding oil to said duct, a Venturi tube in said casing for discharging atomized oil from said nozzle, a steam chamber in said casing surrounding a portion of said nozzle, said adjustable nozzle forming a control valve for the steam chamber with the restricted portion of said Venturi tube, a jacket in said casing surrounding said Venturi tube, and in heat-exchanging relationship therewith, and means for introducing a cooling medium to said jacket. 80

4. An apparatus for gasifying oil, comprising a casing, an oil chamber within said casing, a nozzle in said casing having a valve controlled oil duct extending centrally therethrough, said duct communicating with said oil chamber, an annular chamber in said nozzle surrounding said duct, a steam chamber in said casing surrounding a portion of said nozzle, a Venturi tube in said casing leading from said steam chamber and duct for discharging atomized oil and steam, a jacket in said casing surrounding said Venturi tube and in heat-exchanging relationship therewith, and means for introducing a cooling medium to said jacket and annular chamber. 90

5. An apparatus for gasifying oil, comprising a casing, an oil chamber in said casing, an adjustable nozzle in said casing, a valve controlled oil duct extending centrally through said nozzle and communicating with said oil chamber, an annular chamber in said nozzle surrounding said duct, a Venturi tube in said casing for discharging atom- 100

ized oil, a steam chamber in said casing enclosing a portion of said nozzle, said adjustable nozzle forming a control valve for said steam chamber with the restricted portion of said Venturi tube, a jacket in said casing surrounding said Venturi tube, and in heat-exchanging relationship therewith communicating ports between said jacket and annular chamber, and means for introducing a cooling medium to said jacket.

10 In testimony whereof I affix my signature.
